UNITED STATES PATENT OFFICE.

JOHN A. WEAVER, OF GREELEY, COLORADO.

WHIP HOLDER AND STRETCHER.

SPECIFICATION forming part of Letters Patent No. 755,555, dated March 22, 1904.

Application filed October 10, 1903. Serial No. 176,559. (No model.)

To all whom it may concern:

Be it known that I, JOHN A. WEAVER, a citizen of the United States of America, residing at Greeley, in the county of Weld and State 5 of Colorado, have invented certain new and useful Improvements in Whip Holders and Stretchers; and I do declare the following to be a full, clear, and exact description of the invention, such as will enable others skilled 10 in the art to which it appertains to make and use the same, reference being had to the accompanying drawings, and to the letters of reference marked thereon, which form a part of this specification.

15 My invention relates to improvements in a device for holding and stretching a whip, the object being to keep the whip straight at all times. It is well known that when a whip is new it is perfectly straight, or approximately so, 20 but after it has been used for some time there is a tendency for its upper extremity to bend downwardly. The object of my improved device, as above indicated, is to prevent this tendency by providing a device in which the 25 whip may be kept stretched, so that it is perfectly straight when not in use. Hence by the use of my improvement it is believed that a whip can be kept perfectly straight until worn out.

30 The invention consists of a yieldingly-supported device with which one extremity of the whip is connected and a clamping device adapted to grasp a part of the whip remote from the said extremity. The tension of the 35 yielding device may be regulated at pleasure. When in use, as shown in the accompanying drawings, the cracker extremity of the whip is caught by the yielding or spring-actuated device and the whip is pulled downwardly until it is perfectly straight, after which a part 40 of it remote from the cracker end is slipped into the clamp, whereby the whip is held in the stretched position.

Having briefly outlined my improved construction as well as the objects I expect to accomplish thereby, I will proceed to describe the same in detail, reference being made to the accompanying drawings, in which is illustrated an embodiment thereof. It must be 45 understood, however, that while I have shown

and will hereinafter describe in detail a specific construction adapted to accomplish the desired end I am not limited to the specific construction shown, since it is evident that many other forms of construction may be devised which will accomplish the same end 55 without departing from the spirit of the invention.

In the drawings, Figure 1 illustrates my improved device showing the whip in place, 60 the latter being partly broken away for lack of room on the sheet, it being desired to show the two members of the device on a suitable scale in this view. Fig. 2 is a side view of the upper member of the construction shown 65 in Fig. 1 or a view looking in the direction of the arrow in Fig. 1. Fig. 3 is a perspective view in detail of the holding device for the cracker end of the whip. Fig. 4 is a perspective view in detail of the plate upon which 70 the device shown in Fig. 3 is mounted. Fig. 5 is a perspective view in detail of the clamping device.

It will be observed from an inspection of the drawings that my improved device consists of 75 two members—namely, the member with which the cracker end of the whip is connected and the clamping device which engages the body part or handle of the whip remote from its small or cracker end. Let A designate the holding member, and B the clamping member, each member being considered in its entirety. The member A is provided with a plate A', having apertures in its extremities, through which are passed screws or other suitable fastening devices A², whereby the plate is fixedly secured to a suitable stationary support C. Punched out of this plate A' near each extremity is a lug A³, extending at right angles to the body of the plate. Each of these 80 lugs is provided with an opening in which is inserted a pin or small rod A⁴, the extremities of the pin being preferably held in place by riveting. Upon this rod A⁴ is mounted a device having a claw extremity A⁵, a part A⁶ 85 extending inwardly from the claw to the plate A', a part A⁷ extending downwardly from the part A⁶ and in engagement with the plate A', and a part A⁸ extending outwardly from the lower extremity of the part A⁷ and at right 90 angles to the body of the plate. The part A⁸ is provided with a slot A⁹ through which a pin A¹⁰ may be passed, the pin A¹⁰ being held in place by riveting. The part A⁷ is provided with a slot A¹¹ 95 through which a pin A¹² may be passed, the pin A¹² being held in place by riveting. The part A⁸ is provided with a slot A¹³ through which a pin A¹⁴ may be passed, the pin A¹⁴ being held in place by riveting. The part A⁷ is provided with a slot A¹⁵ 100 through which a pin A¹⁶ may be passed, the pin A¹⁶ being held in place by riveting. The part A⁸ is provided with a slot A¹⁷ through which a pin A¹⁸ may be passed, the pin A¹⁸ being held in place by riveting. The part A⁷ is provided with a slot A¹⁹ through which a pin A²⁰ may be passed, the pin A²⁰ being held in place by riveting. The part A⁸ is provided with a slot A²¹ through which a pin A²² may be passed, the pin A²² being held in place by riveting. The part A⁷ is provided with a slot A²³ through which a pin A²⁴ may be passed, the pin A²⁴ being held in place by riveting. The part A⁸ is provided with a slot A²⁵ through which a pin A²⁶ may be passed, the pin A²⁶ being held in place by riveting. The part A⁷ is provided with a slot A²⁷ through which a pin A²⁸ may be passed, the pin A²⁸ being held in place by riveting. The part A⁸ is provided with a slot A²⁹ through which a pin A³⁰ may be passed, the pin A³⁰ being held in place by riveting. The part A⁷ is provided with a slot A³¹ through which a pin A³² may be passed, the pin A³² being held in place by riveting. The part A⁸ is provided with a slot A³³ through which a pin A³⁴ may be passed, the pin A³⁴ being held in place by riveting. The part A⁷ is provided with a slot A³⁵ through which a pin A³⁶ may be passed, the pin A³⁶ being held in place by riveting. The part A⁸ is provided with a slot A³⁷ through which a pin A³⁸ may be passed, the pin A³⁸ being held in place by riveting. The part A⁷ is provided with a slot A³⁹ through which a pin A⁴⁰ may be passed, the pin A⁴⁰ being held in place by riveting. The part A⁸ is provided with a slot A⁴¹ through which a pin A⁴² may be passed, the pin A⁴² being held in place by riveting. The part A⁷ is provided with a slot A⁴³ through which a pin A⁴⁴ may be passed, the pin A⁴⁴ being held in place by riveting. The part A⁸ is provided with a slot A⁴⁵ through which a pin A⁴⁶ may be passed, the pin A⁴⁶ being held in place by riveting. The part A⁷ is provided with a slot A⁴⁷ through which a pin A⁴⁸ may be passed, the pin A⁴⁸ being held in place by riveting. The part A⁸ is provided with a slot A⁴⁹ through which a pin A⁵⁰ may be passed, the pin A⁵⁰ being held in place by riveting. The part A⁷ is provided with a slot A⁵¹ through which a pin A⁵² may be passed, the pin A⁵² being held in place by riveting. The part A⁸ is provided with a slot A⁵³ through which a pin A⁵⁴ may be passed, the pin A⁵⁴ being held in place by riveting. The part A⁷ is provided with a slot A⁵⁵ through which a pin A⁵⁶ may be passed, the pin A⁵⁶ being held in place by riveting. The part A⁸ is provided with a slot A⁵⁷ through which a pin A⁵⁸ may be passed, the pin A⁵⁸ being held in place by riveting. The part A⁷ is provided with a slot A⁵⁹ through which a pin A⁶⁰ may be passed, the pin A⁶⁰ being held in place by riveting. The part A⁸ is provided with a slot A⁶¹ through which a pin A⁶² may be passed, the pin A⁶² being held in place by riveting. The part A⁷ is provided with a slot A⁶³ through which a pin A⁶⁴ may be passed, the pin A⁶⁴ being held in place by riveting. The part A⁸ is provided with a slot A⁶⁵ through which a pin A⁶⁶ may be passed, the pin A⁶⁶ being held in place by riveting. The part A⁷ is provided with a slot A⁶⁷ through which a pin A⁶⁸ may be passed, the pin A⁶⁸ being held in place by riveting. The part A⁸ is provided with a slot A⁶⁹ through which a pin A⁷⁰ may be passed, the pin A⁷⁰ being held in place by riveting. The part A⁷ is provided with a slot A⁷¹ through which a pin A⁷² may be passed, the pin A⁷² being held in place by riveting. The part A⁸ is provided with a slot A⁷³ through which a pin A⁷⁴ may be passed, the pin A⁷⁴ being held in place by riveting. The part A⁷ is provided with a slot A⁷⁵ through which a pin A⁷⁶ may be passed, the pin A⁷⁶ being held in place by riveting. The part A⁸ is provided with a slot A⁷⁷ through which a pin A⁷⁸ may be passed, the pin A⁷⁸ being held in place by riveting. The part A⁷ is provided with a slot A⁷⁹ through which a pin A⁸⁰ may be passed, the pin A⁸⁰ being held in place by riveting. The part A⁸ is provided with a slot A⁸¹ through which a pin A⁸² may be passed, the pin A⁸² being held in place by riveting. The part A⁷ is provided with a slot A⁸³ through which a pin A⁸⁴ may be passed, the pin A⁸⁴ being held in place by riveting. The part A⁸ is provided with a slot A⁸⁵ through which a pin A⁸⁶ may be passed, the pin A⁸⁶ being held in place by riveting. The part A⁷ is provided with a slot A⁸⁷ through which a pin A⁸⁸ may be passed, the pin A⁸⁸ being held in place by riveting. The part A⁸ is provided with a slot A⁸⁹ through which a pin A⁹⁰ may be passed, the pin A⁹⁰ being held in place by riveting. The part A⁷ is provided with a slot A⁹¹ through which a pin A⁹² may be passed, the pin A⁹² being held in place by riveting. The part A⁸ is provided with a slot A⁹³ through which a pin A⁹⁴ may be passed, the pin A⁹⁴ being held in place by riveting. The part A⁷ is provided with a slot A⁹⁵ through which a pin A⁹⁶ may be passed, the pin A⁹⁶ being held in place by riveting. The part A⁸ is provided with a slot A⁹⁷ through which a pin A⁹⁸ may be passed, the pin A⁹⁸ being held in place by riveting. The part A⁷ is provided with a slot A⁹⁹ through which a pin A¹⁰⁰ may be passed, the pin A¹⁰⁰ being held in place by riveting. The part A⁸ is provided with a slot A¹⁰¹ through which a pin A¹⁰² may be passed, the pin A¹⁰² being held in place by riveting. The part A⁷ is provided with a slot A¹⁰³ through which a pin A¹⁰⁴ may be passed, the pin A¹⁰⁴ being held in place by riveting. The part A⁸ is provided with a slot A¹⁰⁵ through which a pin A¹⁰⁶ may be passed, the pin A¹⁰⁶ being held in place by riveting. The part A⁷ is provided with a slot A¹⁰⁷ through which a pin A¹⁰⁸ may be passed, the pin A¹⁰⁸ being held in place by riveting. The part A⁸ is provided with a slot A¹⁰⁹ through which a pin A¹¹⁰ may be passed, the pin A¹¹⁰ being held in place by riveting. The part A⁷ is provided with a slot A¹¹¹ through which a pin A¹¹² may be passed, the pin A¹¹² being held in place by riveting. The part A⁸ is provided with a slot A¹¹³ through which a pin A¹¹⁴ may be passed, the pin A¹¹⁴ being held in place by riveting. The part A⁷ is provided with a slot A¹¹⁵ through which a pin A¹¹⁶ may be passed, the pin A¹¹⁶ being held in place by riveting. The part A⁸ is provided with a slot A¹¹⁷ through which a pin A¹¹⁸ may be passed, the pin A¹¹⁸ being held in place by riveting. The part A⁷ is provided with a slot A¹¹⁹ through which a pin A¹²⁰ may be passed, the pin A¹²⁰ being held in place by riveting. The part A⁸ is provided with a slot A¹²¹ through which a pin A¹²² may be passed, the pin A¹²² being held in place by riveting. The part A⁷ is provided with a slot A¹²³ through which a pin A¹²⁴ may be passed, the pin A¹²⁴ being held in place by riveting. The part A⁸ is provided with a slot A¹²⁵ through which a pin A¹²⁶ may be passed, the pin A¹²⁶ being held in place by riveting. The part A⁷ is provided with a slot A¹²⁷ through which a pin A¹²⁸ may be passed, the pin A¹²⁸ being held in place by riveting. The part A⁸ is provided with a slot A¹²⁹ through which a pin A¹³⁰ may be passed, the pin A¹³⁰ being held in place by riveting. The part A⁷ is provided with a slot A¹³¹ through which a pin A¹³² may be passed, the pin A¹³² being held in place by riveting. The part A⁸ is provided with a slot A¹³³ through which a pin A¹³⁴ may be passed, the pin A¹³⁴ being held in place by riveting. The part A⁷ is provided with a slot A¹³⁵ through which a pin A¹³⁶ may be passed, the pin A¹³⁶ being held in place by riveting. The part A⁸ is provided with a slot A¹³⁷ through which a pin A¹³⁸ may be passed, the pin A¹³⁸ being held in place by riveting. The part A⁷ is provided with a slot A¹³⁹ through which a pin A¹⁴⁰ may be passed, the pin A¹⁴⁰ being held in place by riveting. The part A⁸ is provided with a slot A¹⁴¹ through which a pin A¹⁴² may be passed, the pin A¹⁴² being held in place by riveting. The part A⁷ is provided with a slot A¹⁴³ through which a pin A¹⁴⁴ may be passed, the pin A¹⁴⁴ being held in place by riveting. The part A⁸ is provided with a slot A¹⁴⁵ through which a pin A¹⁴⁶ may be passed, the pin A¹⁴⁶ being held in place by riveting. The part A⁷ is provided with a slot A¹⁴⁷ through which a pin A¹⁴⁸ may be passed, the pin A¹⁴⁸ being held in place by riveting. The part A⁸ is provided with a slot A¹⁴⁹ through which a pin A¹⁵⁰ may be passed, the pin A¹⁵⁰ being held in place by riveting. The part A⁷ is provided with a slot A¹⁵¹ through which a pin A¹⁵² may be passed, the pin A¹⁵² being held in place by riveting. The part A⁸ is provided with a slot A¹⁵³ through which a pin A¹⁵⁴ may be passed, the pin A¹⁵⁴ being held in place by riveting. The part A⁷ is provided with a slot A¹⁵⁵ through which a pin A¹⁵⁶ may be passed, the pin A¹⁵⁶ being held in place by riveting. The part A⁸ is provided with a slot A¹⁵⁷ through which a pin A¹⁵⁸ may be passed, the pin A¹⁵⁸ being held in place by riveting. The part A⁷ is provided with a slot A¹⁵⁹ through which a pin A¹⁶⁰ may be passed, the pin A¹⁶⁰ being held in place by riveting. The part A⁸ is provided with a slot A¹⁶¹ through which a pin A¹⁶² may be passed, the pin A¹⁶² being held in place by riveting. The part A⁷ is provided with a slot A¹⁶³ through which a pin A¹⁶⁴ may be passed, the pin A¹⁶⁴ being held in place by riveting. The part A⁸ is provided with a slot A¹⁶⁵ through which a pin A¹⁶⁶ may be passed, the pin A¹⁶⁶ being held in place by riveting. The part A⁷ is provided with a slot A¹⁶⁷ through which a pin A¹⁶⁸ may be passed, the pin A¹⁶⁸ being held in place by riveting. The part A⁸ is provided with a slot A¹⁶⁹ through which a pin A¹⁷⁰ may be passed, the pin A¹⁷⁰ being held in place by riveting. The part A⁷ is provided with a slot A¹⁷¹ through which a pin A¹⁷² may be passed, the pin A¹⁷² being held in place by riveting. The part A⁸ is provided with a slot A¹⁷³ through which a pin A¹⁷⁴ may be passed, the pin A¹⁷⁴ being held in place by riveting. The part A⁷ is provided with a slot A¹⁷⁵ through which a pin A¹⁷⁶ may be passed, the pin A¹⁷⁶ being held in place by riveting. The part A⁸ is provided with a slot A¹⁷⁷ through which a pin A¹⁷⁸ may be passed, the pin A¹⁷⁸ being held in place by riveting. The part A⁷ is provided with a slot A¹⁷⁹ through which a pin A¹⁸⁰ may be passed, the pin A¹⁸⁰ being held in place by riveting. The part A⁸ is provided with a slot A¹⁸¹ through which a pin A¹⁸² may be passed, the pin A¹⁸² being held in place by riveting. The part A⁷ is provided with a slot A¹⁸³ through which a pin A¹⁸⁴ may be passed, the pin A¹⁸⁴ being held in place by riveting. The part A⁸ is provided with a slot A¹⁸⁵ through which a pin A¹⁸⁶ may be passed, the pin A¹⁸⁶ being held in place by riveting. The part A⁷ is provided with a slot A¹⁸⁷ through which a pin A¹⁸⁸ may be passed, the pin A¹⁸⁸ being held in place by riveting. The part A⁸ is provided with a slot A¹⁸⁹ through which a pin A¹⁹⁰ may be passed, the pin A¹⁹⁰ being held in place by riveting. The part A⁷ is provided with a slot A¹⁹¹ through which a pin A¹⁹² may be passed, the pin A¹⁹² being held in place by riveting. The part A⁸ is provided with a slot A¹⁹³ through which a pin A¹⁹⁴ may be passed, the pin A¹⁹⁴ being held in place by riveting. The part A⁷ is provided with a slot A¹⁹⁵ through which a pin A¹⁹⁶ may be passed, the pin A¹⁹⁶ being held in place by riveting. The part A⁸ is provided with a slot A¹⁹⁷ through which a pin A¹⁹⁸ may be passed, the pin A¹⁹⁸ being held in place by riveting. The part A⁷ is provided with a slot A¹⁹⁹ through which a pin A²⁰⁰ may be passed, the pin A²⁰⁰ being held in place by riveting. The part A⁸ is provided with a slot A²⁰¹ through which a pin A²⁰² may be passed, the pin A²⁰² being held in place by riveting. The part A⁷ is provided with a slot A²⁰³ through which a pin A²⁰⁴ may be passed, the pin A²⁰⁴ being held in place by riveting. The part A⁸ is provided with a slot A²⁰⁵ through which a pin A²⁰⁶ may be passed, the pin A²⁰⁶ being held in place by riveting. The part A⁷ is provided with a slot A²⁰⁷ through which a pin A²⁰⁸ may be passed, the pin A²⁰⁸ being held in place by riveting. The part A⁸ is provided with a slot A²⁰⁹ through which a pin A²¹⁰ may be passed, the pin A²¹⁰ being held in place by riveting. The part A⁷ is provided with a slot A²¹¹ through which a pin A²¹² may be passed, the pin A²¹² being held in place by riveting. The part A⁸ is provided with a slot A²¹³ through which a pin A²¹⁴ may be passed, the pin A²¹⁴ being held in place by riveting. The part A⁷ is provided with a slot A²¹⁵ through which a pin A²¹⁶ may be passed, the pin A²¹⁶ being held in place by riveting. The part A⁸ is provided with a slot A²¹⁷ through which a pin A²¹⁸ may be passed, the pin A²¹⁸ being held in place by riveting. The part A⁷ is provided with a slot A²¹⁹ through which a pin A²²⁰ may be passed, the pin A²²⁰ being held in place by riveting. The part A⁸ is provided with a slot A²²¹ through which a pin A²²² may be passed, the pin A²²² being held in place by riveting. The part A⁷ is provided with a slot A²²³ through which a pin A²²⁴ may be passed, the pin A²²⁴ being held in place by riveting. The part A⁸ is provided with a slot A²²⁵ through which a pin A²²⁶ may be passed, the pin A²²⁶ being held in place by riveting. The part A⁷ is provided with a slot A²²⁷ through which a pin A²²⁸ may be passed, the pin A²²⁸ being held in place by riveting. The part A⁸ is provided with a slot A²²⁹ through which a pin A²³⁰ may be passed, the pin A²³⁰ being held in place by riveting. The part A⁷ is provided with a slot A²³¹ through which a pin A²³² may be passed, the pin A²³² being held in place by riveting. The part A⁸ is provided with a slot A²³³ through which a pin A²³⁴ may be passed, the pin A²³⁴ being held in place by riveting. The part A⁷ is provided with a slot A²³⁵ through which a pin A²³⁶ may be passed, the pin A²³⁶ being held in place by riveting. The part A⁸ is provided with a slot A²³⁷ through which a pin A²³⁸ may be passed, the pin A²³⁸ being held in place by riveting. The part A⁷ is provided with a slot A²³⁹ through which a pin A²⁴⁰ may be passed, the pin A²⁴⁰ being held in place by riveting. The part A⁸ is provided with a slot A²⁴¹ through which a pin A²⁴² may be passed, the pin A²⁴² being held in place by riveting. The part A⁷ is provided with a slot A²⁴³ through which a pin A²⁴⁴ may be passed, the pin A²⁴⁴ being held in place by riveting. The part A⁸ is provided with a slot A²⁴⁵ through which a pin A²⁴⁶ may be passed, the pin A²⁴⁶ being held in place by riveting. The part A⁷ is provided with a slot A²⁴⁷ through which a pin A²⁴⁸ may be passed, the pin A²⁴⁸ being held in place by riveting. The part A⁸ is provided with a slot A²⁴⁹ through which a pin A²⁵⁰ may be passed, the pin A²⁵⁰ being held in place by riveting. The part A⁷ is provided with a slot A²⁵¹ through which a pin A²⁵² may be passed, the pin A²⁵² being held in place by riveting. The part A⁸ is provided with a slot A²⁵³ through which a pin A²⁵⁴ may be passed, the pin A²⁵⁴ being held in place by riveting. The part A⁷ is provided with a slot A²⁵⁵ through which a pin A²⁵⁶ may be passed, the pin A²⁵⁶ being held in place by riveting. The part A⁸ is provided with a slot A²⁵⁷ through which a pin A²⁵⁸ may be passed, the pin A²⁵⁸ being held in place by riveting. The part A⁷ is provided with a slot A²⁵⁹ through which a pin A²⁶⁰ may be passed, the pin A²⁶⁰ being held in place by riveting. The part A⁸ is provided with a slot A²⁶¹ through which a pin A²⁶² may be passed, the pin A²⁶² being held in place by riveting. The part A⁷ is provided with a slot A²⁶³ through which a pin A²⁶⁴ may be passed, the pin A²⁶⁴ being held in place by riveting. The part A⁸ is provided with a slot A²⁶⁵ through which a pin A²⁶⁶ may be passed, the pin A²⁶⁶ being held in place by riveting. The part A⁷ is provided with a slot A²⁶⁷ through which a pin A²⁶⁸ may be passed, the pin A²⁶⁸ being held in place by riveting. The part A⁸ is provided with a slot A²⁶⁹ through which a pin A²⁷⁰ may be passed, the pin A²⁷⁰ being held in place by riveting. The part A⁷ is provided with a slot A²⁷¹ through which a pin A²⁷² may be passed, the pin A²⁷² being held in place by riveting. The part A⁸ is provided with a slot A²⁷³ through which a pin A²⁷⁴ may be passed, the pin A²⁷⁴ being held in place by riveting. The part A⁷ is provided with a slot A²⁷⁵ through which a pin A²⁷⁶ may be passed, the pin A²⁷⁶ being held in place by riveting. The part A⁸ is provided with a slot A²⁷⁷ through which a pin A²⁷⁸ may be passed, the pin A²⁷⁸ being held in place by riveting. The part A⁷ is provided with a slot A²⁷⁹ through which a pin A²⁸⁰ may be passed, the pin A²⁸⁰ being held in place by riveting. The part A⁸ is provided with a slot A²⁸¹ through which a pin A²⁸² may be passed, the pin A²⁸² being held in place by riveting. The part A⁷ is provided with a slot A²⁸³ through which a pin A²⁸⁴ may be passed, the pin A²⁸⁴ being held in place by riveting. The part A⁸ is provided with a slot A²⁸⁵ through which a pin A²⁸⁶ may be passed, the pin A²⁸⁶ being held in place by riveting. The part A⁷ is provided with a slot A²⁸⁷ through which a pin A²⁸⁸ may be passed, the pin A²⁸⁸ being held in place by riveting. The part A⁸ is provided with a slot A²⁸⁹ through which a pin A²⁹⁰ may be passed, the pin A²⁹⁰ being held in place by riveting. The part A⁷ is provided with a slot A²⁹¹ through which a pin A²⁹² may be passed, the pin A²⁹² being held in place by riveting. The part A⁸ is provided with a slot A²⁹³ through which a pin A²⁹⁴ may be passed, the pin A²⁹⁴ being held in place by riveting. The part A⁷ is provided with a slot A²⁹⁵ through which a pin A²⁹⁶ may be passed, the pin A²⁹⁶ being held in place by riveting. The part A⁸ is provided with a slot A²⁹⁷ through which a pin A²⁹⁸ may be passed, the pin A²⁹⁸ being held in place by riveting. The part A⁷ is provided with a slot A²⁹⁹ through which a pin A³⁰⁰ may be passed, the pin A³⁰⁰ being held in place by riveting. The part A⁸ is provided with a slot A³⁰¹ through which a pin A³⁰² may be passed, the pin A³⁰² being held in place by riveting. The part A⁷ is provided with a slot A³⁰³ through which a pin A³⁰⁴ may be passed, the pin A³⁰⁴ being held in place by riveting. The part A⁸ is provided with a slot A³⁰⁵ through which a pin A³⁰⁶ may be passed, the pin A³⁰⁶ being held in place by riveting. The part A⁷ is provided with a slot A³⁰⁷ through which a pin A³⁰⁸ may be passed, the pin A³⁰⁸ being held in place by riveting. The part A⁸ is provided with a slot A³⁰⁹ through which a pin A³¹⁰ may be passed, the pin A³¹⁰ being held in place by riveting. The part A⁷ is provided with a slot A³¹¹ through which a pin A³¹² may be passed, the pin A³¹² being held in place by riveting. The part A⁸ is provided with a slot A³¹³ through which a pin A³¹⁴ may be passed, the pin A³¹⁴ being held in place by riveting. The part A⁷ is provided with a slot A³¹⁵ through which a pin A³¹⁶ may be passed, the pin A³¹⁶ being held in place by riveting. The part A⁸ is provided with a slot A³¹⁷ through which a pin A³¹⁸ may be passed, the pin A³¹⁸ being held in place by riveting. The part A⁷ is provided with a slot A³¹⁹ through which a pin A³²⁰ may be passed, the pin A³²⁰ being held in place by riveting. The part A⁸ is provided with a slot A³²¹ through which a pin A³²² may be passed, the pin A³²² being held in place by riveting. The part A⁷ is provided with a slot A³²³ through which a pin A^{324</}

angles to the last-named part. The two parts A⁶ and A⁸ are parallel with each other, and each is provided with an opening A⁹, through which the rod A⁴ passes, whereby the holding device is slidably mounted on the rod. Between the part A⁸ of the holding device and the lug A³ of the plate is located a coil-spring A¹⁰, which surrounds the pin A⁴, its upper extremity bearing against the part A⁸ and its lower extremity against the lug A³. The tension of this spring is such that it will normally hold the claw-shaped device at its upward limit of movement. The part A⁷ of the claw is flat and of sufficient area to prevent any tendency of the claw to turn upon the rod A⁴ when the parts are assembled, since the part A⁷ is in contact with the outer face of the plate A'. This obviates any tendency of the claw to twist about while in use. The clamp, as shown in the drawings, consists of a plate B' and a piece of spring metal having jaws B² and a circular part B³. The plate B' is provided with openings B⁴, in which screws or other suitable fastening devices can be inserted. The two members A and B are located at a suitable distance from each other, according to the length of the whip with which they are to be used.

From the foregoing description the use and operation of my improved device will be readily understood. The cracker end of the whip D is provided with a knot D', which is caught in the claw A⁵ of the holding device. The user then pulls down on the whip until the spring A¹⁰ is compressed to give it the necessary or desired tension, after which the handle D² of the whip is slipped into the clamp, the latter being of sufficient tension or strength to prevent the handle from slipping when the latter is once in place. It is evident that when the whip is thus placed in position in the members of my improved device it will be held perfectly straight, and it is believed that if the whip when not in use is kept in this device it will be kept perfectly straight at all times and substantially in the same condition, so far as this feature is concerned, as when new.

Having thus described my invention, what I claim is—

1. A whip holder and stretcher comprising two members, one of which is provided with a yieldingly-retained device adapted to engage one part of the whip, and a clamping device adapted to engage the other part of the whip, the two parts being arranged to hold the whip securely in place, the yieldingly-retained part being bodily movable in a line connecting the two parts.

2. The combination of a yieldingly-retained holding device and a clamping device, the two parts being located in suitable proximity to each other, and one of the parts being bodily movable in a line connecting the two parts. 60

3. In a whip-holder, the combination of two separated devices adapted to engage two different parts of the whip, one of the said devices being yieldingly retained, vertically movable bodily and having a pair of rigid jaws. 65

4. The combination of two devices located in suitable proximity to each other for holding a whip, one of the said devices being spring-retained, and bodily movable in a line connecting the two devices. 70

5. The combination of two members, one member consisting of a plate, a pin mounted thereon, a claw slidably mounted on the pin, and a spring surrounding the pin and acting on the claw; the other member consisting of a device adapted to receive and hold a part of the whip remote from the claw, the latter being adapted to receive the cracker end of the whip. 75

6. The combination of two members, one member consisting of a plate, a pin mounted thereon, a claw slidably mounted on the pin and having a flat part engaging the plate to prevent the claw from turning, and a spring surrounding the pin and acting on the claw; the other member consisting of a clamping device adapted to hold the part of the whip remote from the claw. 80

7. The combination of two members, one member consisting of a plate provided with a pin, a holding device slidably mounted on the pin and comprising a claw, two parallel parts provided with openings through which the pin passes, and a part extending at right angles to the parallel parts and engaging the face of the plate to prevent the claw from turning, and a spring surrounding the pin and bearing upon one of the parallel parts of the claw; the other member consisting of a device provided with clamping-jaws adapted to receive and hold the part of the whip remote from its small end. 90

8. A whip-holder comprising a yieldingly-retained claw and a clamping device, the two parts being suitably separated, the claw being bodily movable in a line connecting the two devices. 100

In testimony whereof I affix my signature in presence of two witnesses.

JOHN A. WEAVER.

Witnesses:

CHARLES E. CLARK,
HARPER C. BENNETT.
